UNITED STATES PATENT OFFICE.

WILLIAM LEWIS, OF UTICA, NEW YORK.

SPRING SEAT OR BED.

1,262,814.

Specification of Letters Patent. Patented Apr. 16, 1918.

Application filed July 28, 1916. Serial No. 111,840.

To all whom it may concern:

Be it known that I, WILLIAM LEWIS, a citizen of the United States of America, and resident of Utica, in the county of Oneida, 5 in the State of New York, have invented new and useful Improvements in Spring Seats or Beds, of which the following, taken in connection with the accompanying drawings, is a full, clear, and exact description.

10 This invention relates to certain improvements in spring seats or beds in which the main supporting body comprises a system of spiral or helical springs arranged side by side, preferably in rows, with their axes ex- 15 tending in the same general direction, and refers more particularly to means for muf- fling or reducing to a minimum the noise or click due to the striking of the convolutions of each individual spring or those of differ- 20 ent springs one against the other.

The superiority of springs of this character, both as to comfort and durability is generally recognized, with the result that they are extensively used in the more expensive 25 beds and other upholstered furniture, and also in the upholstered seats and backs of automobiles and similar vehicles.

It is well-known, however, that when 30 these springs are assembled in the supporting frame in the usual manner and compressed by pressure, the convolutions are brought more or less suddenly into contact, thus producing a clicking or grating sound 35 which is materially amplified by the vibrations of the more free convolutions throughout the length of the coils, in a manner somewhat similar to the sound produced by the ordinary striker gong of a clock.

40 The main object, therefore, of my present invention is to not only reduce to a minimum the possibility of grating contact of the convolutions of adjacent springs of the various rows, but also to muffle as far as possible 45 the vibrations incidental to the contact of one convolution with another, thereby rendering the entire set of springs practically noiseless.

Other objects and uses relating to specific 50 parts of the device will be brought out in the following description.

In the drawings—

Figure 1 is a top plan of a spring seat or bed embodying the features of my invention 55 but omitting the cover and pad.

Fig. 2 is an enlarged sectional view taken on line 2—2, Fig. 1.

In order that my invention may be clearly understood, I have shown a system of spiral or helical springs —1—, preferably of the 60 double cone type, arranged side by side in longitudinal and transverse rows and in substantially the same horizontal plane.

In this instance, all of the springs are of 65 the same size, the end convolutions being of considerably greater diameter than the intermediate convolutions which gradually diminish in diameter from the ends toward the center, thus producing the double cone effect, previously referred to.

Certain convolutions, in this instance, those at the ends of the springs of the several 70 rows are yieldingly connected by relatively small binder coils —2— of spring wire, 75 which binder coils, in this instance, run lengthwise of the several rows and are interlaced with diametrically opposite sides of the end convolutions of the springs so that 80 portions thereof not only embrace the outer edges of the end convolutions of the outer lengthwise rows, but also the adjacent edges of those of the several rows so that the lower and upper ends of all the springs are tied 85 to each other by the binder coils to hold them in relatively fixed relation and normally in parallelism axially, at the same time permitting them to flex axially under pressure.

Furthermore, if pressure is applied on any 90 particular point in the entire surface of the system of spiral springs, the binder coils will serve to distribute the load from such point to adjacent springs, thus causing the 95 entire surface of the system to conform more closely to the contour of the object pressing thereon, which conserves the life and resiliency of the springs and affords a more luxuriant seat or bed without adding materially to the cost of production.

Furthermore, by the use of these binding 100 coils, the adjacent lower and upper edges of the several rows of springs are held in closer contact without in any way diminishing the flexibility of the connection, thereby avoiding the snapping or grating sound incidental 105 to the use of the usual clips or connecting chains.

Another and more important feature of 110 my invention for reducing the noise incidental to the use of helical springs of this

character consists in inserting a muffler pad or pads —3— between the end and next adjacent convolutions of each helical spring in such manner that portions of the muffler 5 pads will be held in place by the tension of such convolutions toward each other, while other portions will project through the openings in such convolutions, as shown more clearly in Fig. 2, so that said convolutions will be practically embedded in the muffler pads.

These pads may be made in strips to extend to two or more adjacent helical springs, and, in this instance, are of sufficient length 15 to extend the entire length of each row and may be made of felt, cotton batting or equivalent substance of sufficient thickness to fill the space between the adjacent convolutions under normal tension.

20 When the pads are thus placed in operative position, the wire convolutions engaged therewith soon become embedded therein and operate to retain them in place, thus obviating the necessity of extra means of 25 securing.

These pads also serve to muffle any sound which may be caused by the relative movement between the helical springs and the binding coils, and furthermore they prevent 30 any possibility of bringing the end convolutions into contact with the next adjacent convolutions where the click and grating usually occurs.

Another important advantage is that 35 when any portion of the system of springs is subjected to pressure, the muffler pads will be similarly depressed into contact with the intermediate convolutions, thereby neutralizing, or, at least, deadening the vibrations which would otherwise be transmitted 40 to said intermediate convolutions.

It is now clear that the binder coils assist 45 in reducing the noise of action of the coil springs without interfering with the flexibility of the entire system, and, in fact, materially aid in such flexibility by transmitting the pressure applied at any one point to other springs in the immediate vicinity thereof, while the muffler pads further 50 reduce the liability of noise in the action of the springs by preventing contact between the end and next adjacent convolutions and by preventing the vibration of the intermediate convolutions, all of which contributes 55 materially to the art of spring seats and beds, in addition to providing a relatively smooth surface over which the usual felt or

fabric coverings, as —4—, may be drawn and secured in place without liability of mutilation by the noise of the springs, the 60 pad being then covered with the usual fac-
ing —5— of leather or equivalent material.

The bottom or back of the seat or system of springs may be supported upon or secured to any suitable frame or support, not 65 shown, since the manner of supporting the system of springs is immaterial and forms no part of my present invention.

What I claim is:

1. In a spring seat or bed, the combination of the system of helical springs having their ends of greater diameter than their intermediate portions and muffler pads nested in said enlarged ends in spaced relation axially and extending between the end 75 convolutions and next adjacent convolutions to prevent contact between said convolutions.

2. In a spring seat or bed, the combination of a row of helical springs arranged 80 side by side with their axes extending in the same general direction, and a muffler padding inserted between the outer end convolutions and next adjacent convolutions of the several springs.

3. In a spring seat or bed, the combination of a spiral spring, and a muffler pad inserted between one of the end convolutions and the next adjacent convolution of said 90 spring.

4. In a spring seat or bed, the combination of a spiral spring having its convolutions gradually diminishing in diameter from the ends toward the center, and muffler pads inserted between both of the end convolutions and the next adjacent convolutions apart from each other.

5. In a spring seat or bed, the combination of a system of spiral springs, each gradually diminishing in diameter from the 100 ends toward the center, said springs being arranged side by side in rows with their axes in parallelism, and muffler pads inserted between both of the end convolutions and next adjacent convolutions of the several spiral springs in spaced relation axially 105 so as to leave the intermediate convolutions free.

In witness whereof I have hereunto set my hand this 17th day of July, 1916.

WILLIAM LEWIS.
